CLAIM

The ornamental design for a waste paper collection container, as shown.

DESCRIPTION

FIG. 1 is a perspective view of the waste paper collection container of my invention;

FIG. 2 is a front view of the device;

FIG. 3 is a left hand side view of the device;

FIG. 4 is a right hand side view of the device;

FIG. 5 is a top view of the device;

FIG. 6 is a bottom view of the device; and,

FIG. 7 is a rear view of the device.
